(57) **CLAIM**

The ornamental design for vertical cash drawer, as shown and described.

DESCRIPTION

FIG. 1 is a top view of a vertical cash drawer showing my new design.

FIG. 2 is a bottom view thereof.

FIG. 3 is a front view thereof.

FIG. 4 is a right side view thereof.

FIG. 5 is a rear view thereof.

FIG. 6 is a left side view thereof; and,

FIG. 7 is an isometric view thereof.

Color forms no part of the claimed design.

1 Claim, 7 Drawing Sheets
